UNITED STATES PATENT OFFICE.

JOHN MEE, OF DORCHESTER, MASSACHUSETTS.

SWIMMING-SHOE.

1,202,083.

Specification of Letters Patent. Patented Oct. 24, 1916.

Application filed February 5, 1916. Serial No. 76,463.

To all whom it may concern:

Be it known that I, JOHN MEE, a citizen of the United States, residing at Dorchester, in the county of Suffolk, in the State of Massachusetts, have invented a certain new and useful Improvement in Swimming-Shoes, of which the following is a specification, reference being had to the accompanying drawings.

10 The object of this invention is to provide an effective, and reasonably cheap, form of webbed shoe by the aid of which a swimmer may increase his speed materially; my present improvement consisting essentially of a 15 novel construction of hinged web, that is foldably mounted on a shoe sole, adapted to automatically open so as to present a broad surface to the water at each rearward, or pushing, movement of the foot, and to close 20 automatically at each forward movement of the foot of the wearer, in order to "feather" or fold the web and thus offer but slight resistance to the water.

For the purpose of clearly explaining my 25 said invention I have provided the annexed drawings, in which—

Figure 1 is a side elevation of a "swimming shoe" embodying my present improvement, and Fig. 2 is an under side 30 plan view of said shoe, the hinged web being partly broken away to show more clearly the hinged ribs to which the web is secured. Fig. 3 is a transverse, sectional view taken on the line 3—3 of said Fig. 2 35 and Fig. 4 is a relatively enlarged detail view of one of the hinge connections.

Referring to these drawings, the numeral 10 denotes a shoe of ordinary make having its heel built up, by addition of an extension 11 to a height equal, or about equal, to the height of the web extension when said web is spread open as seen in the drawings, this provision of the heel extension being made to relieve the strain upon the web 45 when the wearer of the shoe is standing or walking on the ground. Secured to the shoe sole, and extending longitudinally of said sole is a substantial metal plate 12 whose front end portion is extended to provide a rigid horn 13. Along the opposite edges of the plate 12 are several extensions 14 to which are hinged ribs 15 whose outer ends are connected by flexible cords 16 to which is secured, by stitching, or otherwise, a web 50 17 of, preferably, rubberized cloth. The web is also extended forwardly and secured

to the horn 13 and to cords or wires 18 which connect the free end of the horn with the outer ends of the next adjacent ribs 15. The web, and its side supports, as described, 60 are adapted to be readily folded, as indicated by the dotted lines in Fig. 3 or to be extended to approximately a flat position as in full lines in said Fig. 3; the opening movement of the web being, however, limited by 65 ribs 19 that are raised along the opposite edges of the shoe sole. To prevent the ribs 15 from folding too closely together I have extended the inner ends of the said ribs beyond the hinge, as at 15^a and so that said 70 extension will abut the plate portion 14 before the ribs 15 assume a right angular relation to the shoe sole. The web is then held open so that the water may readily enter between the opposing folded sides of the web 75 when the wearer is about to push his foot rearward in the act of swimming. The rigid horn 13, at the front of the shoe, serves as a support for the front end portion of the web.

Having thus described my invention, I claim as new and wish to secure by Letters Patent:—

1. In combination with a shoe-sole, a plate 85 fixedly secured to said sole and formed with a rigid extension at one end, said rigid extension being angular in longitudinal direction, its outer end portion being deflected or inclined forwardly, and downwardly, a plurality of arms hinged to the said plate, and a flexible web secured to the said arms and said rigid extension.

2. In combination with a shoe-sole, a plate 95 fixedly secured to said sole and formed with a rigid extension at one end, said sole being equipped along its longitudinal edges with longitudinal ribs to control the opening movement of the web and said rigid extension being angular in longitudinal direction, its outer end portion being deflected or inclined forwardly and downwardly, a plurality of arms hinged to the opposite edges of said plate, and a flexible web secured to the said arms and said rigid extension.

3. A swimming shoe, including a plate 105 secured longitudinally of the bottom of the shoe, said plate having a plurality of spaced extensions at its lateral edges and a rigid longitudinal extension at its forward end, said longitudinal extension being angular 110 in longitudinal direction, the outer end portion thereof being inclined downwardly

and forwardly, a plurality of ribs hinged to said plate lateral extensions, with their inner ends extending inwardly beyond their hinges and adapted to engage said lateral extensions to control the movement of said ribs with respect to each other, a flexible connection between said ribs and longitudinal extension, and a web applied to said

ribs and secured to said flexible connection and to said rigid longitudinal extension, said 10 shoe having secured to the bottom of its sole, along the longitudinal edges thereof, opposite ribs, the inner ends of said hinged ribs engaging said sole-attached ribs to control the outward movement of the latter ribs.

JOHN MEE.

Copies of this patent may be obtained for five cents each, by addressing the "Commissioner of Patents Washington, D. C."
